UNITED STATES PATENT OFFICE.

ROBERT H. PHILLIPS, OF KENSINGTON, MARYLAND.

TRACK CONSTRUCTION.

Application filed May 12, 1923. Serial No. 638,519.

To all whom it may concern:

Be it known that I, ROBERT H. PHILLIPS, a citizen of the United States, and a resident of Kensington, in the county of Montgomery and State of Maryland, have invented certain new and useful Improvements in Track Constructions, of which the following is a specification.

This invention relates to certain new and useful improvements in track construction for steam and electric railways of the open track or slotted conduit type.

The fundamental purposes of the invention is to effect material saving in the replacement and up-keep costs of both the rolling stock and the track by designing the latter in a novel manner to eliminate or reduce to a minimum the noise, wear and pounding action incident to the passage of the rolling stock thereover.

An equally important purpose of the invention is to reduce the cost of installing the track by designing the component parts in a novel manner to facilitate production and assembly thereof.

A more specific purpose of the invention is to provide an improved supporting yoke or beam presenting rail mounting portions bridging spaced points of support and possessing sufficient inherent elasticity to provide for a slight flexion or yielding thereof between said supports when subjected to the weight of the rolling stock passing over the track rails.

A further specific purpose of the invention is to provide a resilient supporting bed for the yokes designed to provide for a slight bodily movement of the latter in such manner as to effect further cushioning of the track rails.

Other objects and advantages of the invention not specifically stated above will become apparent from the following detailed description and accompanying drawings illustrating what I now consider to be the preferred embodiment of the principles involved.

In the drawings:

Fig. 1 is a transverse sectional view of a railway constructed in accordance with my invention, the slotted conduit rail support-

ing yokes and certain other elements being shown in side elevation.

Fig. 2 is a view in side elevation clearly illustrating the relative position of the yokes, 55 the yoke supporting stringers and the supporting plates underlying said stringers.

Fig. 3 is a perspective view of the improved yoke.

Fig. 4 is a plan view of the yoke and 60 stringer construction disclosed in Figs. 1 and 2.

Fig. 5 is a view similar to Fig. 1, but illustrating the principles of the invention, as applied to an electric or steam railway of 65 the open track type.

Referring more particularly to the drawings, Figs. 1 to 4, inclusive, illustrate the principles of my invention as applied to the construction of an electric railway of the 70 slotted conduit type. As represented in these figures, the track rails 5 and 6 are supported in position by a series of transverse extending yokes 7 constructed of steel or other material possessing the required degree of elasticity. 75

In accordance with the purposes of my invention, it is necessary that the yokes 7 have the capability of yielding to provide an elastic support for the rails 5 and 6 and to 80 this end each yoke is fabricated to present a pair of horizontal rail bearing beams 8 formed integral at their inner ends with a depending U-shaped yoke 9 and at their outer ends with depending post members 10, 85 the lower extremities of the latter being directed laterally to provide the supporting feet 11. As herein shown, the said yokes are mounted with the feet 11 and loop 9 resting, respectively, on the outer and intermediate longitudinally extending stringers 12 which are also constructed of steel or 90 equally elastic metal and, for the purposes of this invention, may conveniently consist of sections of discarded track rails. At 95 points intermediate the said yokes, the stringers 12 are supported by metal plates 13 of predetermined size and thickness which in turn are disposed to rest firmly on a concrete bed 14 which is laid in position prior 100 to the positioning of the previously mentioned elements.

Preferably, the stringers 12, the plates 13 and the lower portions of the yoke 7 are anchored in relative position by welding or by embedding the same in a further filling 5 of concrete or other cementitious material 15 superimposed on the bed 14.

The space between the post members 10 and the loop 9 of each yoke is occupied by a filling of concrete or similar blocks 16, which 10 are extended between the loops of the several yokes to provide the required conduit or trough for the reception of the current conductors. It will also be noted in this connection that the inner ends of the beam 8 15 are utilized to support the slot rails 17 and the space between these rails and the track rails 5 and 6 is occupied by the usual surface material represented by the numeral 18.

My purpose in making the slot or conduit 20 of separate blocks bonded together instead of molding the conduit of concrete in accordance with the prevailing practice, is to enable sectional repairs to be made to the portions of the conduits extending between 25 the several yokes.

By making the yoke 7 of steel design as shown, I obtain an elastic support for the rails 5 and 6 and thereby obviate the usual noise and deterioration of equipment resulting from the pounding action of the rolling stock on the rails during passage thereover. In this connection, it is pointed out that the rail bearing beams 8 being supported to bridge the spaced points of support afforded 35 by the post members 10 and the sides of the loop member 9 are capable of a limited degree of flexion intermediate these points of support when subjected to the weight of the rolling stock passing over the rails 5 and 6. This deflection, while exceedingly slight, is sufficient to provide an effective cushion for the rails 5 and 6.

In addition to the aforementioned flexion of the rail bearing beams 8, I attain additional cushioning of the track rails by reason of the particular arrangement and construction of the stringers 12 and underlying supporting plates 13. As shown to advantage in Fig. 4, the plates 13 provide spaced 45 points of support between which the stringers 12, by reason of the elastic material composing the same are capable of a slight vertical flexion sufficient to permit corresponding bodily movement of the yoke 7 50 when subjected to the weight of the rolling stock. From this, it will be seen that I obtain a double cushioning effect for the track rails by reason of the flexion of the stringers 12 between the supports 13 in addition to 55 the flexion of the rail bearing beams 8 between the spaced points of support formed integral therewith.

In Fig. 5 of the drawings, I have shown 60 the principles of the invention as applied 65 to the construction of an electric or steam

railway of the open or paved track type without a conduit. The yokes 7, stringers 12 and plate 13 are of substantially the same construction as illustrated in the preceding figures, the only material difference 70 being that the supporting posts 10 at the ends of the yoke and the intermediate loop 9 are made of considerably less height so as to dispose the rails 5 and 6 in closer proximity to the concrete bed 14. This change 75 results in a saving of material in the construction of the yokes and is permissible in view of the fact that no conduit is required in this type of railway and hence there is no necessity for making the loop 9 of the 80 depth disclosed in Fig. 1. In fact, it would be within the scope of my invention as applied to an open track railway to eliminate the intermediate loop 9 and the posts 10 and to make the rail bearing beams 8 in one 85 continuous length supported at the ends and at an intermediate point on the stringers 12. In this modified form of the invention, the yokes are embedded in the customary ballast material 19 superimposed on the filling of concrete 20 in which the stringers 12 and plates 13 are embedded.

While in the foregoing I have disclosed what is now considered to be the preferred embodiment it is to be understood that various changes in the construction, arrangement and proportion of parts may be resorted to within the scope of the appended claims without departing from the spirit of the invention.

What I claim and desire to cover by Letters Patent is:

1. In a track construction, the combination of a series of rail bearing yokes and a resilient supporting structure for said yokes 105 having the capability of yielding to permit of a slight bodily movement of the yokes under the weight of the rolling stock.

2. In a track construction, the combination of a series of rail bearing yokes constructed of elastic metal fabricated to provide a resilient support for the rails and means supporting and holding said yokes in 115 position without interfering with the resilient action thereof.

3. In a track construction, the combination of a series of resilient rail bearing yokes capable of a slight flexion in the rail bearing portion to provide a resilient support for the rails and a resilient supporting structure for the yokes having the capability of yielding to permit a slight bodily movement of the yokes vertically when subjected to the weight of the rolling stock.

4. In a track construction, the combination of spaced transverse rail bearing beams, spaced longitudinally extending stringers underlying and supporting said beams at points out of vertical alignment with the 130

rail bearing portions of the beams and a plurality of spaced supports underlying each stringer at points intermediate the said beams.

5. The track construction specified in claim 4, in which the rail bearing beams are constructed of material possessing sufficient elasticity to provide for a slight yielding flexion of the beams at points intermediate the stringers.

6. The track construction specified in claim 4 in which both the rail bearing beams and the stringers are constructed of metal possessing sufficient inherent elasticity to provide for resilient flexion of the beams intermediate the stringers and a like flexion of the stringers intermediate the underlying stringer supports.

7. In a track construction, the combination of a series of spaced transverse yokes presenting each a pair of horizontal rail bearing beams integrally connected at the inner ends by a depending loop and at the outer end to depending supporting posts, longitudinally extending stringers underlying said posts and loop to support the yoke in position and stringer supports underlying said stringers at points intermediate said yoke.

8. A track construction, as specified in claim 7, in which the yokes and stringers are constructed of metal possessing sufficient inherent elasticity to permit of a slight resilient flexion of the rail bearing beams and the portions of the stringers underlying the said yokes.

9. In a track construction, the combination of a concrete bed, spaced series of longitudinally extending stringers positioned thereon, a series of spaced transverse rail bearing yokes supported on said stringers and a plurality of supports interposed between the bottom of each stringer and the concrete bed and positioned at points intermediate said yokes and a concrete filling material embedding said stringers and underlying supports therein.

10. In a track construction, the combination of a concrete bed, spaced parallel series of longitudinally extending stringers embedded in the concrete, a plurality of spaced supporting plates also embedded in the concrete beneath each of said stringers to provide spaced points of rigid support therefor and a series of transversely extending yokes supported on said stringers at points intermediate the underlying stringer supports, said yokes being constructed of metal possessing sufficient inherent elasticity to permit a slight flexion of the rail bearing portions of the yokes.

11. In a railway track construction, the combination of spaced supports, a resiliently flexible beam resting on and bridging between said supports and track rails se-

cured on the beam, said beam flexing between said supports to yield underload on said rails to thereby cushion the travel of cars over said rails.

12. A yoke of the character described presenting rail bearing beams bridging spaced points of support formed integral therewith, said yoke being constructed of metal possessing sufficient inherent elasticity to provide for a slight resilient flexion of the beams intermediate said support.

13. In a track of the character described, a bed structure comprising a series of longitudinally extending stringers arranged in spaced parallelism and a series of spaced supports underlying each stringer, said stringers being constructed of metal possessing sufficient inherent elasticity to provide for a slight flexion of the stringers intermediate said supports.

14. A bed structure according to claim 5 in which the stringers and underlying supports are embedded in a supporting concrete foundation.

15. In a track construction, the combination of transversely extending rail bearing beams and a plurality of transversely spaced stringers underlying each beam at points out of vertical alignment with the rail bearing portions of the beam.

16. The track construction specified in claim 4, in which the stringers are constructed of elastic metal, to provide for vertical flexion of the stringers intermediate the underlying stringer supports.

17. A yoke presenting aligned rail bearing beams, a center support connected to and depending from the inner ends of the beams and a pair of outer supports connected to and depending from the outer ends of the beams.

18. In a railway track construction the combination of rigid supporting members arranged in spaced rows with the members of each row spaced apart, a flexible stringer resting on the top of and bridging between the supporting members of each series, cross beams engaging with said stringers intermediate said supporting members and rail beams secured to said cross beams, said stringers flexing between said supporting members to yield under load on said rails to thereby cushion the travel of cars over said rails.

19. In a railway track construction the combination of a vertically flexible stringer, vertical supports engaging at intervals with said stringer but said stringer being free between said supports to flex vertically, cross beams resting on said stringer intermediate its supporting points and a rail secured on said cross beams.

20. In a railway track construction the combination of a rigid supporting structure comprising spaced apart members, an inter-

mediate supporting structure supported on said members and bridging therebetween and a track structure comprising cross beams and rails directly secured thereon, said cross beams engaging with said intermediate supporting structure intermediate the aforesaid members and said supporting structure

being vertically flexible whereby to yield to permit bodily vertical give of said track structure during travel of loads thereon.

In testimony whereof I hereunto affix my signature.

ROBERT H. PHILLIPS.
